CLAIM

The ornamental design for a baseplate with grip extension, as shown and described.

DESCRIPTION

FIG. 1 is a top, front, and first-side perspective view of a baseplate with grip extension showing our new design; FIG. 2 is top, front, and second-side perspective view thereof;

FIG. 3 is a rear and first-side perspective view thereof;

FIG. 4 is a rear and second-side perspective view thereof;

FIG. 5 is a first-side elevational view thereof;

FIG. 6 is a second-side elevational view thereof;

FIG. 7 is a front elevational view thereof;

FIG. 8 is a rear elevational view thereof;

FIG. 9 is a top plan view thereof; and,

FIG. 10 is a bottom plan view thereof.

Broken lines in the drawings are for the purpose of illustrating environmental structure and form no part of the claimed design.
